(57) **CLAIM**

We claim the ornamental design for a motorcycle gas cap, as shown and described.

DESCRIPTION

FIG. 1 is a first top elevation view of the motorcycle gas cap, with the latch engaged, showing our novel design; FIG. 2 is a second top elevation view thereof, with the latch disengaged;

FIG. 3 is a bottom elevation view thereof;

FIG. 4 is a left side view thereof;

FIG. 5 is a right side view thereof;

FIG. 6 is a front plan view thereof;

FIG. 7 is a rear plan view thereof;

FIG. 8 is a first perspective view thereof;

FIG. 9 is a second perspective view thereof, with the gas cap and flange shown separately; and,

FIG. 10 is a third perspective view thereof, with the dashed lines representing a gas tank of a motorcycle and the dashed lines are not part of the claimed invention.
